(57) **CLAIM**

The ornamental design for a hand held vacuum, as shown and described.

DESCRIPTION

FIG. 1 is a perspective view of a hand held vacuum taken from the rear and one side, showing my new design; FIG. 2 is a perspective view thereof, taken from below and the side shown in FIG. 1;

FIG. 3 is a front elevational view thereof;

FIG. 4 is a rear elevational view thereof;

FIG. 5 is a side elevational view thereof, taken from the side opposite that illustrated in FIG. 1;

FIG. 6 is a side elevational view thereof, taken from the side illustrated in FIG. 1;

FIG. 7 is a top plan view thereof; and,

FIG. 8 is a bottom plan view thereof.
